United States Patent Office.

JOHN DAVIS, OF ALLEGHENY CITY, PENNSYLVANIA.

Letters Patent No. 83,474, dated October 27, 1868.

IMPROVEMENT IN TELLURIUMS.

The Schedule referred to in these Letters Patent and making part of the same.

To all whom it may concern:

Be it known that I, JOHN DAVIS, of the city and county of Allegheny, and State of Pennsylvania, have invented certain new and useful Improvements in Astronomical Apparatus for Illustrating the Motion of the Earth and Moon around the Sun, and the Rotation of the Sun on his Axis; and I do hereby declare that the following is a full, clear, and exact description thereof, reference being had to the accompanying drawings, and to the letters and figures of reference marked thereon.

The nature of my invention consists in so constructing an astronomical apparatus that it will illustrate the rotation of the sun on his axis, the revolving of the earth around the sun, the inclination of the earth on her axis, and the revolving of the pole of the earth around the pole of the ecliptic, and also the revolving and the elliptical motion of the moon around the earth, her crossing and recrossing the plane of the ecliptic, and the retrogression of her nodes.

To enable others skilled in the art of constructing astronomical instruments and apparatus to make and use my invention, I will proceed to describe its construction and operation.

In the accompanying drawings, which form part of my specification—

Figure 1 is a side elevation of my improvement in astronomical apparatus.

Figure 2 is an inverted view of the inclined disk, and the mechanism connected therewith.

Figure 3 is a transverse section of the inclined disk.

In the drawings, A represents the frame of the apparatus, in which are the bearings of the shafts B, C, and D, on which are placed the wheels e, f, g, h, and i. To the frame A is permanently attached the wheel or disk k, by screwing its hub C into the frame. An opening is made in the hub C of the wheel or disk k, for the hollow shaft J of the wheel h.

On the outer end of the shaft J is secured a hollow arm, l, to the outer end of which is secured a piece marked u, the form of which is clearly shown in fig. 2. In the hollow arm, at o, and on the outer end of the piece u, at P, are bearings for the shaft m, on which, at the point marked n, is placed a gear-wheel, which gears into the teeth or cogs on the fixed wheel or disk k. On the outer part of the shaft m are placed wheels R, t, s, and an endless screw, x.

To the piece u are secured three columns, w, to the upper end of which is secured a disk or recessed ring, 14, (see fig. 3,) to which is fitted the bottom of the inclined disk B', and the disk or ring o', which are held in the desired position on the recessed disk or ring 14, by means of three broad-headed screws i', which also hold the recessed disk or ring 14 to its place on the columns w.

To the disk or ring o' is attached a stem, 18, to which is pivoted the arm 11, on the upper end of which is placed the moon m'. The arm 11 is provided with a hook, y, which is hooked under the

flange x' of the inclined disk B', for the purpose of holding the arm 11 and its friction-wheel 12 in proper position with relation to the flange x' of disk B'.

On the under side of the recessed disk or ring 14 is secured a step, marked 3, which is provided with a hollow column, marked 4, over which is placed a hollow shaft, 21, on the upper end of which is a disk, 6, and on the lower end a wheel, x', and in the column 4 is placed and secured a shaft, f', on the upper end of which is a crank, 7, to which is pivoted a disk, 8, to the arm 9 of which, at the point marked 10, is pivoted the earth E'. On the lower end of the shaft f', placed in the hollow column 4, is a wheel, 5, into which gears an endless screw, 15, on the outer end of which is a wheel, 13, which gears into teeth or cogs x on the under side of the inclined disk B'. The endless screw 15 is held in position by means of suitable bearings o' on the under side of the step 3.

On the outer end of the piece u may be secured two wheels, x' and 1, shown in red, the wheel x' being so arranged as to gear into the endless screw x', and the wheel 1 to gear into teeth placed on the periphery o' the inclined disk B'.

The endless screw x', in connection with the wheels x', 1, and teeth 2, on the disk B', shown in red, (see fig. 1,) are represented for the purpose of showing a very desirable method for giving the desired motion to the inclined disk B', for representing the retrogression of the moon's nodes.

The wheel R, on the shaft m, gears into the teeth x on the under side of the disk B', and wheel t gears into the wheel x', and the wheel s gears into the teeth 16 on the under side of the disk o'. The sun s' is placed on the outer end of the shaft B.

As the construction and arrangement of the several parts of my astronomical apparatus, and the relation that the several parts bear to each other, will readily be seen and understood by the skilful mechanic, by reference to the accompanying drawings, and by the foregoing description, I will therefore proceed to describe their operation, which is as follows:

By turning the shaft D, it will revolve the wheel e, which will revolve the shaft C and wheels f and i. The wheel f will revolve the wheel g and shaft B, which will rotate the sun s' on his axis; and the wheel i will revolve the wheel h and shaft J, which will move the arm l around over the disk or fixed wheel k, which will cause the teeth on the disk or wheel k to revolve the wheel n and shaft m, which will revolve the wheels R, t, and s. The wheel R gears into the teeth x of disk B', will revolve it, and the wheel s, gearing into teeth 16 of the disk o', will revolve it, and will thereby revolve the arm 11 and moon m' around the earth E'.

The inclination of the disk B', and its revolution, and that of the disk or ring o' through the medium of the wheels R and s, will impart an elliptical motion to the moon m' around the earth, and will represent her crossing and recrossing the plane of the ecliptic, and also the retrogression of her nodes.

The wheel t , gearing into wheel x^1 , will revolve it, and thereby revolve disk 6, which will revolve the disk 8, which will revolve the earth E' on its axis, and by pivoting the earth at one pole, and it at an angle of twenty-three and a half degrees to the plane of the ecliptic, the plane of the earth's equator will always be at an angle of twenty-three and a half degrees to the plane of the ecliptic; and by revolving the earth around the sun, the earth's yearly motion around the sun, the changes of seasons, the apparent motion or declination of the sun, north and south, and the increase and decrease of day and night during the different seasons of the year, will be completely and perfectly illustrated.

The revolving of the disk B' will cause its cogs or teeth z to revolve the wheel 13, which will revolve the endless screw 15, which will revolve the wheel 5, which will revolve the shaft f^1 and crank, 7, to which the axis or disk 8 is pivoted. By thus pivoting the disk 8 to the crank, 7, and pivoting one pole of the earth to the arm 9 of the disk 8, and revolving the disk and crank, the revolving of the pole of the earth around

the pole of the ecliptic, and the recession of the equinoxes are illustrated, thereby exhibiting and demonstrating to the student that strange and wonderful phenomenon in the science of astronomy.

Having thus described the nature, construction, and operation of my improvement,

What I claim as of my invention, is—

1. Pivoting one pole of the earth to the disk 8, and pivoting it to the crank, 7, and operating said disk and crank through the medium of disk 6, wheels t , x^1 , 5, and endless screw 15, the whole being constructed, arranged, and operating in the manner substantially as herein described, and for the purpose set forth.

2. The inclined disk B' , in combination with disk o^1 , stem 18, and arm 11, provided with friction-wheel 12, said disks being constructed, arranged, and made operative through the medium of the mechanism herein described, and for the purpose set forth.

JOHN DAVIS.
